(57) **CLAIM**

The ornamental design for a ceiling lining panel for an aircraft cabin, as shown and described.

DESCRIPTION

FIG. 1 is a front view of a ceiling lining panel for an aircraft cabin showing my new design; and,

FIG. 2 is a perspective view thereof.

In each of these Figures, the unshown portion of the ceiling lining panel for an aircraft cabin forms no part of the claimed design.

1 Claim, 1 Drawing Sheet

FIG. 1

FIG. 2
